Filed Mar. 22, 1971, Ser. No. 127,067

Term of patent 14 years

Int. Cl. D2—03

U.S. Cl. D2—233

FIG. 1

FIG. 2

FIG. 3

FIG. 4

FIG. 5

FIG. 1 is a side perspective view of a face shield showing my new design;

FIG. 2 is a top plan view thereof;

FIG. 3 is a side elevational view;

FIG. 4 is a bottom plan view; and

FIG. 5 is a back elevational view.

The dominant feature of my design resides in the non-transparent frame member of the face shield, said frame member being of one piece having a visor-like top which conjoins a downwardly extending horizontal front portion and side portions, all of which form the nontransparent member.

I claim:

The ornamental design for a face shield, substantially as shown and described.
